UNITED STATES PATENT OFFICE.

JOHN EDENS, OF DAVENPORT, IOWA, ASSIGNOR TO H. F. BRAMMER MANUFACTURING COMPANY, OF DAVENPORT, IOWA, A CORPORATION OF IOWA.

OPERATING-GEAR MECHANISM FOR WASHING-MACHINES.

No. 893,907.

Specification of Letters Patent.

Patented July 21, 1908.

Application filed March 31, 1908. Serial No. 424,381.

To all whom it may concern:

Be it known that I, JOHN EDENS, a citizen of the United States, and a resident of Davenport, in the county of Scott and State of Iowa, have invented certain new and useful Improvements in Operating-Gear Mechanism for Washing-Machines and the Like; and I do hereby declare that the following is a full, clear, and exact description thereof, 10 reference being had to the accompanying drawings, and to the letters of reference marked thereon, which form a part of this specification.

This invention relates to improvements 15 in operating gear mechanism for washing machines of that type of machine embracing a dasher shaft which is capable of rotary reciprocatory motion in the tub and a vibratory operating lever operating, through 20 the medium of suitable gear connections, to give movement to said shaft, and the invention consists in the matters hereinafter set forth and more particularly pointed out in the appended claims.

25 As shown in the drawings:—Figure 1 is a side elevation of a washing machine equipped with my improved operating gear mechanism. Fig. 2 is a plain view thereof. Fig. 3 is an enlarged vertical section, taken 30 on line 3—3 of Fig. 1. Figs. 4 and 5 are detail views, taken on lines 4—4 and 5—5, respectively, of Fig. 1. Fig. 6 is a perspective view of the rack bar constituting part 35 of the gear connections between the operating lever and dasher shaft.

As shown in the drawings, 10 designates the tub of a washing machine and 11 the hinged lid or cover thereof.

12 designates a vertical dasher shaft carried by and extending upwardly through the cover, and 13 designates a dasher block or dolly carried by the lower end of said shaft. The said dasher shaft extends at its upper end through and has bearing in a 40 frame 15 supported on and attached to the swinging lid, said frame embracing a short bearing sleeve 16 depending from the frame into a central opening in the lid. An upper bearing for the shaft, located a distance 45 above the sleeve 16, is formed in the horizontal part 17 of the spider frame 15. Said dasher shaft extends upwardly beyond said upper bearing and it carries a horizontal balance wheel 18 which is rotatively mount-

ed on the upper end of the shaft. The hub 55 19 of said balance wheel rests on the spider frame 17. The shaft is suspended in its bearings by a pin 20 which extends transversely through the upper end of the shaft above the balance wheel, and rests on a 60 washer 22 supported on the upper end of said wheel hub.

65 A pinion 25 is fixed to the shaft 12 between the upper and lower bearings and meshes with the teeth 26 of a horizontal, endwise reciprocating rack bar 27, which is mounted to slide in the frame 15. Said rack bar extends radially beyond the cover and is pivotally connected, through the medium of a pivot pin 28, with a vertically swinging operating 70 lever 29 located at one side of the tub. The rack bar is guided at its inner end between the pinion 25 and one of the vertical sides of the spider frame 17, and is guided near its outer end between two guide lugs 30, 31 75 which rise from and are made integral with the bearing frame 15, as best shown in Fig. 4. One of said lugs, to wit, the lug 31, carries a horizontal guide roller 32 which is mounted on a pin 33 that extends laterally from the 80 lug 31 and said roller engages the upper side of the rack bar in a manner to hold the same from rising. The rack bar is provided with an offset end 34 which brings the operating lever 29 in a vertical plane which passes 85 through the axis of the dasher shaft and is parallel with the path of reciprocation of the rack bar. The said operating lever 29 is pivoted at its lower end to an arm 36 which is rigid with and extends downwardly from the 90 bearing frame 15 at one side of the tub, said arm being herein shown as made integral with said frame. The pivotal connection between the operating lever and said bearing frame arm 36 is made as follows: The lower 95 end of the arm 36 is provided with a horizontal pin 38 which extends transversely therethrough, at right angles to the rack bar 27, and said pin carries at the sides of said arm bearing rollers 39 which are confined between 100 the arm and a head on one end of said pin and a nut on the other end thereof. The operating lever is provided at its lower end with an inwardly offset forked end piece 40, the lateral members 41 of which extend at either 105 side of the arm 36 and are formed with curved slots 42 which fit over and engage the bearing rollers 39 of the pivot pin 38. The

slotted connection of the operating lever with the pivot pin 38 permits the lower end of the lever to shift in a curved path relatively to the pivot pin during the swinging movement 5 of the lever, and enables the rack bar 27 to move inwardly and outwardly in a straight line notwithstanding its pivoted connection with the swinging lever. Thus proper meshing relation of the rack with the pinion is 10 maintained uniform throughout the entire stroke thereof and the necessity is avoided of providing a loose and unstable pivotal connection between the rack bar and lever. The curvature of the slot will be modified by 15 the length of the offset arm of the end piece of the operating lever, approaching a straight slot as the length of the offset arm diminishes.

The arrangement herein shown is an advantageous one for the reason, among others, 20 that it enables the bearing frame arm 36 to be located closely adjacent to the side of the tub and avoids an objectionable projection of the arm from the tub with a corresponding liability to breakage. By reason of the fact 25 that the arm 36 which supports the pivot pin for the operating lever is made rigid with and carried by the bearing frame and the swinging lid, no necessity arises for disconnecting the lever from the rack bar or from its pivot 30 when the swinging lid of the tub be raised, all parts of the operating mechanism being raised upwardly with the lid.

In order to balance or render uniform the movement of the operating mechanism and 35 to facilitate reversal of the parts at the limits of their reciprocatory movement, the balance wheel 18 is provided which operates in connection with the operating lever 29 in a manner to rotate continuously in the same direction. The operative connections between 40 said lever and balance wheel embrace a pinion 45 rigid with or formed on the hub of the balance wheel 18, a gear wheel 46 meshing with said pinion and rotatively mounted on a 45 stud 47 rising from the bearing frame 15, and a pitman 48 which is pivotally connected at one end with said wheel and at its other end with the operating lever. Said pitman 48 is pivoted at its inner end to a pin or stud 49 50 carried by the gear wheel and is apertured at its outer end for engagement with a hooked shaped stud 50 which is attached to and carried by the operating lever.

I claim as my invention:—

55 1. As a means for imparting rotary reciprocatory motion to a dasher shaft, the combination with the dasher shaft and its bearing frame, of a pinion fixed to the dasher shaft, a horizontal, endwise reciprocatory rack bar 60 intermeshing with said pinion, an oscillatory operating lever pivoted between its ends to said rack bar, and a pivotal connection between said operating lever and a part rigid with the bearing frame comprising an inwardly offset arm on the end of said lever

formed with a curved slot and a bearing pin carried by said part rigid with the frame occupying said slot.

2. As a means for imparting rotary reciprocatory motion to an upright dasher shaft, 70 the combination with said shaft and its bearing frame, of a pinion fixed to the shaft, a horizontal, endwise reciprocatory rack bar intermeshing with said pinion, and an oscillatory operating lever pivoted between its 75 ends to said rack bar, said bearing frame being provided with a rigid, downwardly extending member having at its lower end a bearing pin, and said actuating lever being provided at its lower end with an arm having slotted connection with said bearing pin.

3. As a means for imparting rotary reciprocatory motion to an upright dasher shaft, 85 the combination with said shaft and its bearing frame, of a pinion fixed to the shaft, a horizontal, endwise reciprocatory rack bar intermeshing with said pinion, an oscillatory operating lever pivotally connected between its ends with said rack bar, and means for pivoting said actuating lever to said bearing 90 frame comprising a member rigid with and extending downwardly from one side of said bearing frame and provided with a horizontal pivot pin, and an offset forked arm at the lower end of said lever, the lateral members 95 of which are provided with curved slots which fit over the ends of said pivot pin.

4. As a means for imparting rotary reciprocatory motion to an upright dasher shaft, 100 the combination with said shaft and its bearing frame, of a pinion fixed to the shaft, a horizontal endwise reciprocatory rack bar intermeshing with said pinion, an oscillatory operating lever pivoted between its ends to said rack bar, said bearing frame being provided with a rigid, downwardly extending member having at its lower end a bearing pin, and said actuating lever being provided at its lower end with an arm having slotted connection with said bearing pin, a balance 105 wheel rotatively mounted on said shaft horizontally over said rack bar, and means for operatively connecting said balance wheel 110 with the operating lever in a manner to rotate the balance wheel always in the same 115 direction.

5. As a means for imparting rotary reciprocatory motion to an upright dasher shaft, 120 the combination with said shaft and its bearing frame, of a pinion fixed to the shaft, a horizontal, endwise reciprocatory rack bar intermeshing with said pinion, an oscillatory operating lever pivoted between its ends to 125 said rack bar, said bearing frame being provided with a rigid, downwardly extending member having at its lower end a bearing pin, and said actuating lever being provided at its lower end with an arm having slotted connection with said bearing pin, a balance wheel rotatively mounted on said shaft hori- 130

zontally over said rack bar and provided on its hub with a rigid pinion, a horizontal gear wheel rotatively mounted on a stud rising from said frame and meshing with the balance wheel pinion, and a pitman affording operative connection between said gear wheel and operating lever.

In testimony, that I claim the foregoing as

my invention I affix my signature in the presence of two witnesses, this 26th day of March 10 A. D. 1908.

JOHN EDENS.
